(57) **CLAIM**

The ornamental design for an portable speaker, as shown and described.

DESCRIPTION

FIG. 1 is a top, front and right side perspective view of a first embodiment of a portable speaker, embodying my new design;

FIG. 2 is top plan view;

FIG. 3 is a front elevation view, the rear and right side elevation views being identical;

FIG. 4 is a left side elevation view;

FIG. 5 is a bottom plan view;

FIG. 6 is a top, front and right side perspective view of a second embodiment thereof;

FIG. 7 is a top plan view;

FIG. 8 is a front elevation view;

FIG. 9 is a right side elevation view;

FIG. 10 is a left side elevation view;

FIG. 11 is a bottom plan view;

FIG. 12 is a top, front and right side perspective view of a third embodiment thereof;

FIG. 13 is a top plan view;

FIG. 14 is a front elevation view, the rear, right and left side elevation views being identical; and,

FIG. 15 is a bottom plan view.

The broken lines shown are included for the purpose of illustrating portions of the portable speaker that form no part of the claim.
